UNITED STATES PATENT OFFICE.

EDWARD A. STIGGINS, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR COVERING BOOT AND SHOE STRAPS.

1,127,541.

Specification of Letters Patent.

Patented Feb. 9, 1915.

Application filed August 22, 1908. Serial No. 449,802.

To all whom it may concern:

Be it known that I, EDWARD A. STIGGINS, a citizen of the United States, residing at Beverly, in the county of Essex and Commonwealth of Massachusetts, have invented 5 certain Improvements in Machines for Covering Boot and Shoe Straps, of which the following description, in connection with the accompanying drawings, is a specification, 10 like reference characters on the drawings indicating like parts in the several figures.

This invention relates to machinery for the manufacture of articles of the class including the donning straps or loops which 15 are provided at the rear of the tops of shoes, such a strap being inserted usually in the upper of each shoe early in its formation, and accompanying the shoe throughout the process of manufacture. On account 20 of the rough usage and handling to which the shoe is subjected, the strap requires thorough protection, and this usually takes the form of a covering of paper, serving to prevent the strap from becoming soiled until the shoe is ready for sale. Such 25 coverings may conveniently be applied to the individual straps, in the course of their manufacture from a substantially continuous flexible strip of webbing or other suitable 30 strap stock, and the covers are usually so applied prior to the operation of doubling the strap into the loop form in which it is ready to be inserted in the shoe upper.

My invention is of special utility when 35 embodied in machines of the type in which substantially continuous stock strips of strap and cover material are fed across each other at right angles, suitable portions of each severed from the stock strips respectively, 40 and the resulting strap doubled after having been covered, although I contemplate the use of my invention in any field to which it is adapted by the nature of my improvements, nor indeed do I limit their embodiment 45 to machines for the manufacture of shoe straps.

One of the most important objects of my invention is to provide packing and inclosing mechanism to receive the covered, doubled shoe straps or similar articles, and after assembling these articles in compact bundles each containing a convenient number 50 of the articles, to secure each pack so formed within a suitable inclosure, constituting the parcel thus delivered a merchantable

article ready for the workman's bench, where individual straps may be taken from the parcel at will until all the straps shall have been removed. As this mechanism may be considered a complete invention in itself, 60 I do not make it the subject of separate generic claims in the present application, but reserve the right to file a separate application containing such claims.

Heretofore it has been customary to assemble by hand the covered straps from the loose heaps in which they were discharged by the doubling mechanism, and to bundle them in bulky, irregular packages, difficult 65 to handle and apt to fly apart.

Another important object of my invention is to provide a templet device to sustain the flexible strip or other article in its flat or other desired shape during the 70 operation of covering and creasing, and to 75 coöperate with cover-folding devices in maintaining the cover upon the article without an extraneous adhesive during its dis- 80 sociation from the templet and its introduc- 85 tion to the doubling mechanism. I prefer to provide this templet with a central exit 90 to permit withdrawal of the covered strap by a suitable creasing device transversely from the templet and directly into the dou- 95 bling mechanism, without preliminary dis- placement from its covering relation with the templet. In older types of strap-covering machines, having templets or guides for the cover material, the covered strip has 100 been shifted from the templet longitudinally, and then creased and doubled, and frequently this shift resulted in displacing the cover from proper position. In the most advanced type of strap-covering machines, the covered straps are transferred to the 105 doubling mechanism without preliminary shifting from the covering position, thus avoiding the possibility of displacement of the cover from its proper medial position on the strap, but in these machines no templet has been used, for lack of means to 110 permit transverse withdrawal of the covered strap from a continuous templet. It has also been customary to paste together the overlapping edges of the cover to prevent its displacement from the strap. In apparatus where no templet is used, and the paper cover is folded directly about the strip of flexible strap stock, the strap has a tendency to curl longitudinally under the

110

pressure of the cover paper, especially if thick paper is used, and accordingly it is the general practice to use covering paper too thin for durability, and this paper is 5 crumpled and easily torn by rough usage during the manufacture of the shoe, so that sometimes 25% of the straps lose their covers and are unprotected. The pasting operation itself is also one difficult to accomplish with uniform accuracy and without marring the work, so that a substantial 10 advance in the art has been secured by my provision of means to permit the use of a templet; and also of means to dispense with the use of paste and to maintain a covering of adequately thick paper in place upon the strap during the operations of folding, creasing, doubling, assembling and packing, as hereinafter described.

15 An additional object of my invention is to simplify the process of folding the cover over the strap and to reduce the number of moving parts operative in that process, and this I accomplish preferably by arranging 20 the templet device to move into engagement with a yielding folding-table between which and the templet are first introduced the article to be covered and the cover material, further movement of the templet serving to 25 carry the cover past, and in engagement with, folder members on opposite sides of the table, thus bending the edges of the cover past the edges of the strap, after which a transverse or refolding movement 30 is imparted to the folder members to overlap the edges of the cover above the templet and article, maintaining them in adjusted position until and during withdrawal of the covered strap from the templet, when 35 the folders and templet are returned respectively to normal position, leaving the yielding table to regain its normal position also, in readiness for a fresh supply of cover and strap stock. Heretofore, where movable folding tables have been used, rotating folder 40 members have been mounted on, and movable with the table, but the operating connections for the reciprocating table and rotating folders have been complicated, and 45 the character of the fold is less satisfactory than that produced by the simple, firm, transverse, crowding engagement provided by my novel arrangement of folding members, yielding folding-table and plunging templet.

50 Still other important objects of my invention are: the provision of strap-marking mechanism with means for its adjustment and control independently of the means for adjustment of the mechanism to regulate the 55 length of the article manufactured; improved detector mechanism to govern the operation of the machine and prevent the operation thereof upon defective material; improved gripper mechanism for grasping the work-strip positively to draw it into ac-

curate alignment with the covering material and folding mechanism; also improved cover feeding mechanism; and mechanism for delivering the covered, doubled articles successively, and in uniform position, to the 70 assembling mechanism.

The various features of my invention will be illustrated and described fully in the accompanying drawings and specification and set forth in the claims.

In the drawings, Figure 1 is a view in rear elevation of a machine for manufacturing covered straps; in the construction of which my improvements have been embodied; and Fig. 1^a shows a single, complete 80 strap, covered and folded; while Fig. 1^b shows a bundle of manufactured straps as delivered by my machine, wrapped in a parcel and ready for the workman's bench; Fig. 2 is a view in front elevation of the same machine on a larger scale; and Fig. 2^a is a fragmentary, detail view in perspective, illustrating the templet device and its support; Fig. 3 is a view in side elevation looking from right to left, Fig. 1; and Fig. 4 a 85 view in side elevation looking from left to right, Fig. 1; Fig. 5 is a plan view of the machine, on the same scale as Fig. 2, parts being broken away for the sake of clearness; Fig. 5^a is a fragmentary view, in plan, partly in section, showing the gripper jaws about to draw the stock strip into place for the covering operation; and Fig. 5^b shows in perspective, on a reduced scale, the tension 90 device for the cover strip; Fig. 6 is a fragmentary, detail view in perspective of the web-strip-gate and severing mechanism, shown in its general relation to other parts in Figs. 2 and 5; Fig. 7 is a fragmentary 95 view in transverse, vertical section on the line X⁷—X⁷, Fig. 5, with parts shown in elevation, illustrating the covering and delivery mechanism; and Fig. 8 a similar view of said mechanism looking from left to right on the line X⁸—X⁸, Fig. 5; Fig. 9 is a fragmentary view in horizontal section of the assemblatory and related parts; and Fig. 9^a is a fragmentary detail view in plan showing the wrapper strip gate; Fig. 10 is a fragmentary, detail view in perspective 100 of the assembling mechanism shown in Figs. 2 and 9, parts being omitted to reveal others. Figs. 11-13 inclusive are fragmentary views in perspective of the wrapper-feeding mechanism shown in Fig. 5, and illustrate 105 details of construction to be described more fully hereinafter.

I will first give a brief summary of the general operation of my invention as disclosed in the preferred embodiment thereof selected for illustration and description, and will then describe in detail the preferred mechanism used to accomplish the several operations of feeding, covering, doubling, delivery, assembly, packing, wrapping and 110

discharging, with the subsidiary operation of printing, which I will reserve to the last; and I will describe also the mechanism for controlling the organized machine herein 5 described as a convenient form to enable ready and complete understanding of my improvements.

Summary of operations.—Briefly summarized, and referring first to Fig. 1, my machine for manufacturing covered straps and similar articles may conveniently receive its supply of stock in the form of a substantially continuous work-strip of webbing or other suitable material A, contained 15 in the form of a roll from which the strip is drawn (see Figs. 5^a and 7) by a sliding gripper device B, beneath a temple C, which presses it down upon a strip of covering paper D (see Fig. 7) led thereunder 20 from a supply roll D, formed of said paper, (see Fig. 5, the covering paper not being shown beyond the vicinity of said roll in this figure). The cover is folded around the strip (see Fig. 8) by the action of 25 folders E, E', after which the covered strap is creased by descent of the creasing device F and passed along to doubling rolls G, G', and thence by delivery mechanism H, H' to the slot of a conveyer screw I, (see Fig. 7), 30 whence the assembled, covered straps (each one resembling that shown in Fig. 1^a) pass by an assembly-way K (see Figs. 2, 5 and 10) to one of the slots 1² of a packing-hopper or receptacle L (see Fig. 5) in which 35 they receive a wrapper or inclosure M from the roll M', rotation of the hopper finally bringing them opposite a discharge-way N, from which they are discharged automatically in the parcel form illustrated in Fig. 40 1^b. The printing operation when desired, is performed by a printing device P, (see Fig. 2) acting upon the strip before it receives the preliminary draft into covering position.

45 *Feeding operation.*—Taking up now for description in detail the mechanisms utilized in accomplishing the respective operations above summarized, and for the sake of convenience dividing the mechanisms 50 roughly by operations, (although the description in certain places will not be confined absolutely to mechanism specifically provided for the operation under which it is classified,) I will describe first the supply 55 or feeding operation, starting at the region a at the top of Fig. 2, which the strip a' (see Fig. 1) of webbing or other suitable strap stock has reached after passing between 60 guide pins a² upon the standard a³, which 65 supports the trough or holder a⁴, the latter being provided preferably with an anti-friction roll a⁵, the bearing shaft a⁶ of which is mounted in the wall of the trough, a gate member a⁷ being provided and mounted pivotally at a⁸ adjacent the lip of

the trough, (as shown in Figs. 1 and 3). The end of the shaft a⁶ projects into a slot a⁹ in the gate member arm and limits swinging movement thereof.

Reverting to Fig. 2, the strip portion a 70 is subjected first to the action of a tension and detector device a¹⁰ in the form of a knuckle mounted to rotate with a rock shaft a¹¹, supported rotatably near one end in a bearing a¹², (see Fig. 5), carried by the machine frame part a¹³, the other end of the rock shaft having a bearing a¹⁴ and a collar a¹⁵ between which a coil spring a¹⁶ acts upon the rock shaft to hold the knuckle normally upward toward an abutment a¹⁷, 75 with the web held snugly therebetween, as best seen in Fig. 2. To prevent lateral displacement of the web, a latch a¹⁸ is shown, (see Fig. 5), mounted rotatively upon the end of the rock shaft a¹¹ and held in place 80 by a collar a¹⁹, which permits the latch to be raised into the position shown in Fig. 2, to allow the strip to be placed in position or removed, the latch being movable also 85 into the horizontal position shown in Fig. 5, where it acts to hold the strip in place. A finger-piece a²⁰ is provided preferably, to enable the knuckle to be depressed manually to release the strip portion a, and permit the latter to be inserted, adjusted and 90 removed. This tension knuckle serves also the function of a detector, in the following manner, viz: The rock shaft upon which the knuckle is mounted is extended beyond the bearing a¹⁴ and provided with a shoulder or ledge a²¹, best seen in Fig. 1, and upon this ledge rests a latch a²² pivoted upon a frame member a²³ which is provided with a spring a²⁴, (see Fig. 5), tending normally 95 to hold the latch down against the ledge a²¹ so that a shoulder a²⁵ at the free end of the latch (see Fig. 1) will be in a position 100 to engage and lock a pin a²⁶ upon the shipper handle a²⁷, when the shipper handle is moved toward the left (see Fig. 1). The shipper handle a²⁷ is mounted pivotally 105 upon the frame base (see Fig. 1) at a²⁸, and has a bracket or arm portion a²⁹, connected with a shipper-rod a³⁰, this rod having at 110 its outer end (see Fig. 5), an arm a³¹ connected with a slide rod a³² passing through a rotatable arm a³³ and provided with a belt guide a³⁴, which is held normally opposite the loose pulley a³⁵, as shown in Fig. 1, by 115 action of a coil spring a³⁶ surrounding the rod a³⁰ between the frame part a³⁷ and a collar a³⁸ upon the rod. When the shipper handle is moved to the left (Fig. 1) it takes 120 with it the belt guide a³⁴ and carries the belt (not shown) on to the main actuating pulley a³⁹, this pulley being mounted upon a hollow, bearing stud a⁴⁰ (see Fig. 5), projecting from the frame part a⁴¹, the stud having a longitudinal bore a⁴² to pass 125 the shipper rod a³⁰ and serve as a bearing 130

therefor. The stud a^{10} serves also as a bearing for the arm a^{21} , which is provided with a set-screw to permit the arm to be secured in adjusted rotative position with the guide 5 a^{34} at the proper angle to engage the belt. The main actuating pulley is connected operatively with the various mechanisms of the machine by connections to be described in detail hereinafter.

10 In Fig. 1 the machine is shown with the shipper handle a^{27} out of operative position. To start the machine, the shipper handle is moved to the left, throwing the belt on to the pulley a^{39} by means of the belt guide a^{34} , 15 as already described, and in this position the shipper handle is locked by engagement of the latch a^{22} with the pin a^{26} on the shipper handle. The various mechanisms of the machine will then be operated continuously, by 20 connections to be described, until disengagement of the shipper handle, which may be effected by raising the latch a^{22} manually, or by manual rotation of the rock shaft a^{11} , effected by depressing the finger piece a^{20} , at 25 the front of the machine, this being the most convenient method of stopping the machine at will. I have provided also for automatic stopping of the machine when the strip A is exhausted or when a defective, unusually 30 thick portion reaches the knuckle a^{10} , or when a joint (between the pieces usually making up the rolls of such stock strips) reaches the knuckle. As the thickened portion passes through the knuckle it will draw 35 the latter downward, causing rotation of the rock shaft a^{11} and causing one shoulder of the ledge a^{21} (see Fig. 1) under the latch to lift the latch from engagement with the pin a^{26} on the shipper handle, which is released 40 and then by the action of the coil spring a^{36} the rod a^{20} and belt guide a^{34} are thrown, with the belt, away from the main pulley a^{39} and opposite the pulley a^{35} , cutting off the power and permitting the machine to stop. 45 The same result is attained upon absence of the strip A from between the knuckle a^{10} and the abutment a^{17} by exhaustion of the strip supply, or otherwise, which permits rotation upward of the knuckle a^{10} , and with it the 50 rock shaft a^{11} under the action of the spring a^{16} , the shoulder a^{21} acting as before but in the opposite direction to lift the latch a^{22} and throw it off the pin a^{26} of the shipper handle, stopping the machine. This is the 55 position shown in Fig. 5.

When the machine is operating normally, after the strip A passes the knuckle a^{10} , which holds it under tension, the portion 60 a^{43} of the strip traverses (see Fig. 2) a vertical platen a^{44} with a felt covering a^{45} if found desirable (see Fig. 6) and here the operation of printing may preferably be accomplished by a printing device P (see Fig. 2) which I will describe later. At the lower 65 end of this run the strip is carried around a

positioning spring-foot a^{46} , (best seen in Figs. 5^a and 6), which serves to prevent accidental displacement of the strip end a^{71} rearward (see Fig. 5^a), the foot being mounted pivotally on a stud a^{47} carried by 70 an adjustable supporting member a^{48} , (see Fig. 6) secured by a binding screw a^{49} to the table member a^{50} of the frame. The movable member carries also severing mechanism, consisting in the instance illustrated of a knife a^{51} mounted pivotally on a rock shaft a^{52} in bearings a^{53} upon the movable member a^{48} , and co-operating with a fixed shear member a^{54} also carried by the movable member a^{48} , (see Figs. 5^a and 6). 75 A sill a^{55} is provided preferably on the movable member to aid in positioning properly the strip, and the latter is held in place between the foot a^{46} and the sill a^{55} by a movable latch a^{56} (see Fig. 6) mounted pivotally on the vertical platen a^{44} and having at its lower end an adjustable toe-plate a^{57} secured by a binding screw, and provided also with a spring catch a^{58} which holds the latch in adjusted position. When it is desired to 80 remove the strip a^{43} from between the foot and the sill or to insert a new strip, the upper part of the catch arm is moved toward the right and the latch portion a^{56} moves toward the left and leaves free the narrow 85 opening between the foot and an auxiliary guide member a^{59} , the latter being mounted upon the stationary frame member a^{60} . 90

The length of the individual straps will be controlled by the position of the severing device a^{51} , and the shaft of this severing device, which may be a knife or any device suitable for the purpose, is shown in the instance illustrated (see Fig. 6) as having a segment rack arm a^{61} meshing with another segment arm a^{62} mounted on a stud a^{63} and having a tail piece a^{64} provided with an anti-friction roll which engages the cam track a^{65} on the side of a cam a^{66} carried by the main actuating shaft a^{67} , the latter being 100 rotated (see Fig. 2) through the medium of a gear a^{68} meshing with a pinion a^{69} on the hub a^{70} of the main driving pulley a^{39} of the machine. 110

The stock strip A, a^{43} , when first inserted 115 in the machine is drawn through the knuckle a^{10} (see Fig. 2) past the vertical platen a^{44} and between the foot a^{46} and sill a^{55} (see Figs. 2, 5^a and 6) whence its free end a^{71} projects in position to be grasped by the draft jaws b and b' (see Fig. 5^a), of the movable gripper device B, the first of which jaws is preferably integral with a sliding head b^2 mounted to traverse a slide b^3 carried by the frame table member a^{72} 120 to which it is secured adjustably by screws a^{73} , (see Fig. 2). The slide head b^2 may be adjusted by screws b^4 at each end of the head and these screws engage a wear piece b^5 within the head (see Fig. 5^a). A 125 130

rock shaft b^6 mounted in bearings b^7 upon the head carries at its inner end the movable jaw b' (see Fig. 5^a), and has at its outer end a crank b^8 (see Figs. 2, 3, 5, and 5^a) with a pin b^9 carrying a head b^{10} in and engaging a groove b^{11} in a lever b^{12} mounted pivotally at b^{13} upon the frame. When the lever b^{12} moves toward the right, (see Fig. 2) it first rotates the crank b^8 and the head pin b^9 until the latter strikes an abutment b^{14} (see Fig. 5^a), provided with a regulating screw b^{15} , the rotation of the crank serving to throw the jaw b' upward away from the jaw b , and then the lever b^{12} drives the head b^2 along the slide b^3 until the jaws b and b' are respectively below and above the free end a^{71} of the strip, ready to grasp the same by being moved into the position shown in Fig. 5^a. The lever b^{12} is actuated through the medium of a pin b^{16} secured by a nut b^{17} adjustably within the lever slot b^{18} , the pin having a sliding head b^{19} moving in a slot b^{20} in an intermediate lever b^{21} carried pivotally at b^{22} by the frame member a^{72} and having in turn an arm b^{23} with an anti-friction roller b^{24} which enters a cam groove a^{75} in a cam a^{76} secured suitably, as by a set screw a^{77} upon a cam shaft a^{78} . This shaft is operated by a worm a^{79} (see Fig. 1), meshing with a coöperating spiral gear a^{80} upon the main shaft a^{67} , (see also Fig. 2). As the cam a^{76} turns, and when the point a^{81} is reached, the lever b^{12} receives the beginning 35 of its leftward movement and acts in turn upon the crank b^8 , rotating the same with the rock shaft b^6 and closing the jaw b' down upon the jaw b , gripping therebetween the strap portion a^{71} (see Fig. 5^a). 40 When the jaws are closed, the crank and the rock shaft can no longer rotate and the lever b^{12} thereupon moves the crank and with it the head b^2 , along the slide b^3 toward the left, past the position shown in Fig. 5^a, drawing with it a portion a^{82} of the strip, which constitutes the blank from which the strap is to be manufactured. The parts now occupy the position shown in Fig. 2, and so far as the strap stock is concerned, the supply operation has been completed. Concurrently with the above-mentioned operation, the supply operation upon the cover stock has been performed in a manner which will be understood best upon reference first to Fig. 5, showing the machine in plan, with the roll D of covering paper mounted on a spindle d rotating in cap bearing devices a^{83} at the end of arms a^{84} extending from the frame of the machine. From the roll D the edge d' of the strip is carried forward under an idle roll d^2 having strap-guiding flanges at each end, and mounted pivotally near the free end of arms d^3 extending from the spindle d^4 mounted in bearings a^{85} in the frame of the machine, the paper passing through an auxiliary spring-controlled tension frame d^5 (see Figs. 1 and 5^b) and over a direction member d^6 to and between a pair of feed rolls d^7 and d^8 with intermeshing gears d^9 , d^{10} , having also a gear d^{11} which is driven positively by a gear d^{12} on a short shaft d^{13} which extends through the frame, having at its inner end an interrupted gear d^{14} meshing with an interrupted gear a^{86} upon the main shaft. As the interrupted gear causes the feed rolls to give a sudden pull on the strip of cover stock, it is desirable to provide yielding feed and this may be furnished by the auxiliary tension device shown at d^5 which designates a rod 70 carried by short arms d^{15} mounted pivotally on a rod d^{16} or studs extending between the longer swing arms d^3 , and provided with a coil spring d^{17} which tends normally to take up any slack in the cover strip by pressing the frame and strip into the plane of the swinging arms d^3 . A spring d^{100} may be provided to hold the idler roll d^2 in normal engagement with the roll D, so that its flanges will receive and guide the strip of cover stock properly. The forward end d' of the strip D of covering stock (see Fig. 8) is fed forward by the rolls d^7 and d^8 over a table e across a stationary shear member a^{87} (see Fig. 5) under a shear member d^{18} , 80 and thence under the strap blank portion a^{82} (see Fig. 7) the advanced portion of the covering strip being sufficient in depth to embrace the strap on both sides, with a small margin for overlapping, and this covering portion is then severed from the stock of covering strip by descent of the shear member d^{18} at approximately the same time as the severance of the strap, the shear d^{18} being mounted rotatively upon a rock shaft 85 a^{88} carried in bearing arms a^{89} , a^{90} (see Fig. 5) of the frame of the machine. The member d^{18} has a tail piece a^{91} (best seen in Fig. 7) carrying an anti-friction roll a^{92} which is acted upon by the periphery of a cam a^{93} mounted on, and actuated by the cam-shaft a^{78} already described. A spring a^{94} may be provided to hold the shear d^{18} normally in its upper inoperative position. This completes the supply operation when, as I prefer, the operation of pasting the covering strip is omitted, for by the novel construction of my covering apparatus, now to be described, I have made it possible to avoid the difficult and untidy pasting operation. 110

Covering operation.—At or about the time of severance of the blank a^{82} of strap stock and its blank of cover paper d^{19} just described, I bring into action a templet device C, the general construction of which appears best in Figs. 1 and 2, but the details of which are shown more fully in Figs. 2^a, 5, 7, and 8 to which attention is now directed. This templet, in its preferred form, comprises two plate-like members c , 115

c', (see Fig. 2^a) spaced slightly apart at their free ends *c²* to permit passage of the creasing device F which will be described later, these plates being preferably flat and in the same general plan, with their free ends opposed, cut away slightly in a concave curve as at *c³* respectively and having their corners bent down slightly as at *c⁴* to facilitate withdrawal of the cover edges thereover, and dissociation of the covered strap from the templet. The templet members may be carried and operated by any suitable device, and one convenient form of such device is illustrated (see Figs. 2^a 5 and 7), at *c⁵* taking the form of a yoke carried by an arm *c⁶* preferably fastened medially on the rock shaft *a⁸⁸* and having a tail piece *c⁷* (see Fig. 7) provided with an anti-friction roll *c⁸* which engages, and is 10 operated by, the periphery of a cam *c⁹* on the cam shaft *a⁷⁸*. A spring *c¹⁰* may be provided to hold the templet normally in its upper position. After descent of the templet device C the parts occupy substantially 15 the position illustrated in Fig. 8, with the strap blank *a⁸²* pressed down by the templet C against the cover blank *d¹⁹*, which in turn rests upon the folding-table *e* which I have shown as yielding, being provided for that 20 purpose with a plurality of plungers *e'* entering the pits *a⁹⁵* in a stationary bed member *a⁹⁶* secured by screws upon the frame part *a⁹⁷*, springs *e²* being provided in one or 25 more of the pits to hold the folding table normally up at or about the level on which the cover stock strip is fed over the stationary shear plate *a⁸⁷*. In its descent, the templet C has drawn the strap blank *a⁸²* and the cover blank *d¹⁹* down past two folder 30 blades E, E', (see Fig. 8) which have caused the edges *d'* and *d²⁰* of the paper to turn upward into the position illustrated. The folder blades E and E' are secured by screws *e³* to, and carried respectively by the arms *e⁴* 35 and *e⁵* of levers mounted upon the rock-shafts *e⁶* and *e⁷* carried by the frame members *a⁹⁸* and *a⁹⁹* (see Fig. 2). These levers are shown as having anti-friction rollers *e⁸* and *e⁹* at their lower free ends to be engaged 40 and operated by lateral cam shoulders or ridges *c¹¹* and *c¹²* upon the rotating cam *c⁹*, upon the cam shaft *a⁷⁸*. When the templet C has reached the lowest point in its range of movements, the upper surface of the 45 templet members *c*, *c¹* is about opposite the blades E and E', and the latter member E is then operated by the cam shoulder *c¹¹* to press the upstanding edge *d'* of the cover blank over the top of the templet plates *c*, 50 *c¹*, as indicated in Fig. 8, and thereafter the finger E', actuated a little later by the cam ledge *c¹²* folds the upstanding cover blank edge *d²⁰* over in the opposite direction down upon the templet members *c*, *c¹*, and across 55 the free edge *d'* of the cover blank (see Fig.

7) thus surrounding strap and templet. A spring *e¹⁰* may be provided to hold the members E, E' apart normally out of the path of the templet. By providing a templet, I am able to utilize a thicker and 70 stiffer paper for the cover blank, which has the result that when doubled and compressed, as I will now describe, the cover remains in adjusted position upon the doubled strap without any need for an extraneous adhesive. The machine has now completed the covering operation, the middle of the strap being covered for a distance equal to the width of the covering stock, leaving free its ends to a distance determined by the 75 degree of throw of the gripper B, which throw is determined (see Fig. 2) by the adjustable connection *b¹⁶* between the levers *b¹²* and *b²¹*. The movable member *a⁴⁸* carrying the strap shears *a⁵¹*, *a⁵⁴*, (see Fig. 6) is adjusted 80 to correspond to this throw of the head B and its jaws *b* and *b'*, by loosening the screw *a⁴⁹* and setting it in adjusted position; i.e. the position of the shear *a⁵¹* should be at least as far to the right of the creasing member F as the distance of the jaws *b* and *b'* will be to the left of F when the head B is at its extreme leftward position, the sheared end being preferably a little longer than the other end of the strap, so that when 85 fastened in a shoe, there will not be too much of a lump at the end of the strap. 90

Creasing and doubling operation.—The operation of the creasing device F will be understood best upon reference to Fig. 7. 100 The creasing device itself may take any suitable and convenient form, but I have illustrated herein a form of device consisting of a plurality of spring leaves held adjustably by a nut *f* at the end of an arm *f¹*, which is mounted rotatably at *f²* on the shaft *a⁸⁸* and has a tail portion *f³* with an anti-friction roller *f⁴*, which lies in a cam groove *a¹⁰⁰* on the inner side of the cam *a⁷⁶* mounted upon and operated by the cam shaft *a⁷⁸*. The creasing device F is depressed after completion of the covering operation, and the leaves engage the strap blank and its superimposed cover at the region of the opening between the templet members *c*, *c¹*, (see Fig. 7), the leaves being slightly separated to avoid cutting action upon the paper and strap, and to form a reentrant fold 3 in the bight of the cover (see Fig. 1^a), this permitting the strap to be folded completely flat, a feature which I do not claim as part of my invention. As the creasing device descends it draws the strap from beneath the templet members *c*, *c¹*, respectively, and draws the overlapping cover edges off the templet members, and transversely downward through the exit formed between their slightly separated, opposed free ends *c²*. Further movement of the creasing device forces the double strap downward through 115 120 125 130

an aperture e^{10} in the middle of the bed plate e , this aperture preferably having rounded edges to avoid tearing the paper cover. As already mentioned, the free ends c^2 of the 5 templet plates c , c^1 will preferably be slightly curved as indicated at c^3 in Figs. 2^a and 5, and their corners c^4 bent down slightly to facilitate this smooth withdrawal of the paper cover with the strap during the creasing and doubling operation. Notches e^{11} 10 will preferably be provided in each of the folder blades E , E' to pass the creasing device (see Fig. 5). Below the aperture e^{10} , and as near it as can be conveniently arranged, I prefer to provide a mechanism for 15 doubling and delivering the straps, and this may be of any convenient and suitable form. I have shown it (see Fig. 7) as consisting of a plurality of rolls G , G' , with serrated surfaces g to grip the completed strap, which is now covered and folded, presenting the appearance shown in Fig. 1^a, bearing the reference numeral 1, the reference numeral 2 designating the paper cover, and 3 the re- 20 entrant fold already described.

In accordance with my invention, I prefer to combine with the devices already described, mechanism for more exact delivery of the cover straps than has been accomplished heretofore, and for their assemblage 30 in bundles or parcels wrapped in convenient numbers and form for use by the workman who inserts them in the shoe uppers, and accordingly I have illustrated a second set of 35 doubling and delivery rolls H , H' to which the covered straps are conveyed by belts h , these belts taking conveniently the form of endless spiral springs lying in peripheral grooves g' , (see Figs. 7 and 8). I prefer to 40 actuate the two sets of rolls positively, and to that end have mounted them on shafts g^2 , g^3 , g^4 , g^5 , carried respectively in bearings a^{101} on the frame member a^{90} , the shafts being provided with gears g^6 meshing with 45 each other and with an operating gear g^7 on a stud a^{102} and actuated by a gear a^{103} on the shaft a^{78} . The shaft bearing g^8 of one of the rolls may rest in a slideway as at a^{104} (see Fig. 2) and be normally pressed yield- 50 ingly toward the opposite roll as by a spring g^9 held up to its work by a plate a^{105} secured by screws a^{106} . This construction permits the rolls to separate slightly if an unusually thick strap is delivered to them.

55 *Delivery and assembling mechanism.*— Passing now to the delivery and assembling mechanism proper, the initial step is accomplished upon the passage of the completed strap 1, as seen in Fig. 7, from the lower set 60 of delivery rolls H , H' to a conveyer screw I which has a spiral groove i , into which the covered straps are fed one by one, the screw being mounted (see Fig. 9) on a shaft i' passing through the frame at a^{107} , and rotated by a gear i^2 meshing with an inter-

mediate gear i^4 which is actuated by a gear i^3 carried by the main actuating shaft a^{67} . Upon reference to Figs. 2, 5, 9 and 10, it will be seen that adjacent the screw I is a slideway K which I will hereinafter term an 70 assembly way or assemblatory, having at its sides guide members k , k' and the individual covered straps as they are advanced by the rotation of the screw are confined at the beginning of their path between the guide 75 member k , and the screw-shaft i' (see Fig. 9) so that rotation of the screw gradually carries them forward from the groove of the screw into the portion of the guideway beyond the limits of the screw and between the 80 guide members k , k' , a number of them being shown in this position in Figs. 2, 5 and 10. The wall member k (see Fig. 2) of the assemblyway is secured by screws k^2 , k^3 , to the bottom a^{108} of the assemblyway, which may 85 constitute part of the frame and the corresponding rear wall k' of the assemblyway may be secured similarly by screws as at k^4 , (see Fig. 2), the rear member having a slot k^5 , (see Fig. 10) through which projects a 90 finger k^6 at the end of an arm k^7 extending up from a carriage k^8 which runs upon a rock rail k^9 , the carriage preferably having wheels k^{10} secured in place by suitable means, as the screw piece k^{11} . Suitable 95 means, as the screws k^{12} may be provided to permit adjustment of the finger vertically. The rock rail k^9 is mounted pivotally on bearings preferably provided with means for adjustment, as the screws k^{13} , k^{14} at its 100 ends in the upright members a^{110} , a^{111} of the frame base and when a number of straps (say 48) have been assembled in the assemblyway the finger k^6 is withdrawn rearward from the assemblatory by a rocking movement of the rail, this being accomplished by any suitable mechanism which, in the instance illustrated, takes the form of a lever device k^{15} (see Fig. 10) projecting downward and rearward toward and actuated by 105 a cam ledge a^{112} carried by the horizontal barrel cam a^{113} which appears at the bottom of Figs. 1, 3 and 10, and the contour of which will best be seen by reference to Fig. 10. The rotation of this cam may be accomplished in any convenient manner as by a vertical shaft a^{114} , (see Figs. 1 and 5), at the upper end of which is a spiral gear a^{115} , having a number of teeth corresponding to the number of straps to be bundled, in this 110 instance 48, and which meshes with a worm a^{116} carried by the shaft a^{67} (see Fig. 5). When the finger k^6 is withdrawn from the slot, its carriage is automatically retracted, (see Fig. 10), by a spring k^{16} which replaces 115 the finger in a position adjacent to the first turn of the spiral groove i in front of the strap first to be delivered by said groove, and when the cam a^{113} releases the lever k^{15} , the finger k^6 is thrown forward into the as- 120 125 130

semblyway to engage said straps, by action of a spring k^{17} , which tends normally to rock the rail k^9 forward. A buffer k^{18} may be provided to prevent undue shock at the 5 end of the retractive movement and if desired the head piece k^{19} of the rail k^9 may be made separable therefrom and the other end of the rail formed with an enlargement k^{20} , the general section of the rail being rectangular. Any other suitable construction 10 of rock rail may however be adopted, nor do I limit myself to the exact type of carriage illustrated, which is shown as embracing the rail on three sides and having projections 15 k^{21} to engage the fourth side. Bearing pieces k^{22} may also be provided at the rail ends. To the left, *i. e.* at the rear, of the group of straps which are confined in front thus by the finger k^6 , I provide (see Figs. 20 2, 9 and 10), a feeding finger or packing member k^{23} which engages the assembled group and feeds it forward positively, this finger being mounted upon an arm k^{24} extending upward from a carriage k^{25} mounted 25 on a rock frame comprising a rock rail k^{26} provided with arms k^{27} and a rock rod k^{28} , and carried at each end by bearings in the upright members a^{117} , a^{118} respectively of the frame base. I have shown this rail 30 as rocked by a lever k^{29} (Figs. 4 and 9), which is secured to the rock rail and has at its free end a roll k^{30} operated by a lower outside cam ledge a^{119} on the barrel cam a^{113} , down against which ledge the roll k^{30} is held 35 normally by the action of the coil spring k^{31} (see Fig. 4) secured at k^{32} to the frame member a^{120} . The rail is rocked outward for the purpose of withdrawing the packing member k^{23} to enable it to be returned to 40 the position shown in Figs. 2, 9 and 10 behind the group of straps, this return movement being accomplished by the action of a lever k^{33} (see Fig. 9) which has a segmental rack k^{34} at its free end engaging a 45 straight rack k^{35} upon the carriage k^{25} , the lever k^{33} being mounted pivotally at k^{36} upon a vertical shaft k^{37} to which is fixed a lever arm k^{38} provided with an anti-friction roll k^{39} which enters a cam groove a^{121} on 50 the head of the barrel cam a^{113} . The packing member k^{23} having been positioned by action of the arm k^{33} and the arm k^{29} at the point shown in Figs. 2 and 9 and thrown in by the spring k^{31} , the restraining finger k^6 55 is withdrawn and further operation of the cam a^{113} causes the packing member k^{23} to advance toward the right, pushing with it and compacting the group of 48 covered straps which are now assembled as best 60 shown in Fig. 10, and will be delivered thus, preferably, to the packing mechanism now to be described, and which constitutes one of the most important objects of my invention.

Packing mechanism.—Adjacent to the 65 right-hand end of the assemblyway K is

preferably arranged the packing and wrapping or inclosing mechanism for an understanding of which reference may be made first to Figs. 2 and 5 and, briefly stated, this mechanism comprises a rotating receptacle 70 or hopper L , mounted pivotally at a^{122} upon the frame base (see Fig. 1) and having transverse grooves, slots or recesses l^2 , l^3 , l^4 , l^5 , which may intersect at the center as illustrated in Fig. 5, and each of which is 75 of suitable length to receive a group of the desired number of covered straps. Such a group is shown partly inserted within the groove l^2 where it has been delivered by the right-hand movement of the packing member k^{23} during the period illustrated in Fig. 5 when the entrance of the groove l^2 registers with the exit of the assemblyway K . The member designated by the reference letter l^6 constitutes a gate for the 80 groove and there are similar gates l^6 provided for the other grooves, each of these being provided with suitable means to resist yieldingly the entrance of the strap. For this purpose I have shown each of them as 85 controlled (see Figs. 5 and 11) by one of the springs l^7 lying beneath an extension slide l^8 with which each gate is provided at the bottom of its slot, and operating between an abutment plate l^9 (see Fig. 11) 90 and an extension slide or foot l^{10} of the gate respectively opposite. These springs are coiled respectively each upon a guide rod l^{11} (see Fig. 5) which traverses a hole l^{12} (see Fig. 11) in the foot of its respective gate. Adjacent each guideway is 95 preferably provided a stationary shear member l^{13} , secured removably to the outer wall of the hopper, by suitable fastening means, as the screws l^{14} , for a purpose to be described 100 later.

The wrapping operation.—I carry out the operation of wrapping in bundles or parcels the respective groups of straps preferably at the time that they are packed into the hopper slots by the action of the finger k^{23} , and this wrapping operation I will now describe in such brief detail as may be adequate to a proper understanding of my present invention, a more complete description being reserved for a separate application.

Referring to Fig. 5, the reference numeral M' designates a reel of wrapping paper, or other suitable wrapping or inclosing material, preferably somewhat narrower than the length of the folded strap, the reel being mounted on a vertical stud a^{123} carried by a bracket a^{124} attached by a bolt or other suitable fastening means a^{125} to the frame member a^{120} (see Fig. 1), and the strip M from this reel I lead around a direction stud m and between guide members m' , m^2 , (see Figs. 5, 9 and 9^a), past a knife or other suitable severing mechanism 115 120 125 130 135

m^3 , (see Fig. 9) and into position to be grasped by one of the four gripper devices l^{15} , l^{16} , l^{17} , and l^{18} , provided just to the rear of each of the grooves l^2 , l^3 , l^4 and l^5 , each gripper serving in its turn (see Figs. 9 and 11-13) to grasp the forward end m^4 of the strip M and draw it along in the course of rotation of the hopper into position across the following slot and the gripper being then actuated to release the end of the strip, so that the group of straps when pressed into the slot by the packing member k^{23} will carry into the slot the paper also, (see Fig. 5) drawing its free forward end m^4 back along the clearance space l^9 until a small portion is left in said clearance space as shown partly accomplished at m^4 in Fig. 5. In Fig. 9 the wrapper is shown ready for withdrawal of the finger l^6 and insertion of the straps into the slot l^2 , the straps being omitted to show the assemblyway clearly. During the operation of inserting the straps the hopper remains stationary, and after the group of straps has entirely entered the slot l^2 , before the hopper begins to rotate in the direction of the arrow Fig. 5, carrying with it the partly wrapped straps, the rear of the wrapper will be severed at m^5 from the strip of wrapper stock by action of the knife or severing device m^8 , as shown clearly in Fig. 9. This severing device (see Fig. 9), is carried by a sliding head m^6 , to which the knife is secured adjustably by suitable means, as the screws m^7 , (see Fig. 9) which hold in place a vertical guide m^8 along which the head slides. To actuate the severing device a lever arm m^9 is connected pivotally to the head m^{10} by means of a stud m^{11} which enters a slot in a groove m^{12} in the head, and this lever is mounted rotatively upon the vertical shaft k^{37} at the rear of the machine, the arm having a medial anti-friction device m^{13} , which enters and is operated by a face-track a^{126} in the upper surface of a disk cam a^{127} , the latter being mounted to rotate with the vertical shaft a^{114} . When the lever m^9 is actuated by the cam, the knife is carried forward into engagement with the strip M of paper opposite a vertical recess l^{20} (see Fig. 9) in the exterior wall of the hopper, acting to sever the strip at m^5 by shearing engagement with the shear member l^{13} in advance of the gripper, (see Figs. 9 and 11). At the same time the head m^{10} (see Fig. 9) forces a plunger m^{14} mounted in a recess m^{15} of the head, with a strong spring m^{16} behind it, into engagement with the gate device m' , holding it toward a co-operating fixed gate member m^2 (see Figs. 9 and 9^a) to engage the strip of wrapper stock near the region of severance, and hold it taut, so that the knife will readily pass through and sever it cleanly. The gate m' is pivot-

ed at m^{17} (see Figs. 5 and 9^a) upon a vertical journal a^{128} , the gate being closed normally by a spring m^{18} , (see Fig. 1) and which may be provided with a controlling handle m^{19} . To supplement the binding action of the spring m^{18} , the gate may have an upward extension m^{20} with a cam block m^{22} fastened by a screw m^{23} and to be engaged by a roll m^{21} on the under surface of the spiral gear a^{115} and which holds the gate shut positively and binds the strip M while being severed.

The cycle of the wrapping and packing operation begins at the point illustrated in Fig. 9 where the free end of the strip of wrapper stock is left after severance at m^5 , and the first step in this cycle is accomplished when the vertical rotating gripping device l^{15} turns into engagement with the free forward end m^4 of the severed strip, (see Figs. 11, 12 and 13), and by pressing it against an abutment l^{21} secured by screws l^{22} within a recess or socket l^{23} in the periphery of the hopper, the gripper is enabled in the course of its further movement to grasp the strip M as shown in Fig. 12, and to draw forward the strip from between the gate members m' , m^2 , (see Figs. 9 and 9^a) across the exit of the assemblyway K and in front of the slot l^2 and gate l^6 against which the straps will press the wrapper under the action of the packing member k^{23} as already described see (Fig. 5). The construction of the gripper device l^{15} may vary considerably without departing from the spirit of my invention, and when it takes the form herein shown, of a vertical finger, it is preferably mounted on a vertical journal l^{24} , the upper and lower ends of which are carried in bearings l^{25} of bearing pieces l^{26} secured by screws l^{27} upon the upper and lower faces of the hopper wall l^{28} .

To actuate the gripper device into operative engagement with the free edge of the wrapper strip as already described, any suitable means may be adopted, and as one convenient form of such means, I have shown each of the grippers, (see Figs. 11-13), as provided with an arm l^{29} having a stud l^{30} carrying an anti-friction roll l^{31} , to be brought into engagement, as the hopper rotates, with the concave surface a^{129} of a projection a^{130} extending upward from the bed a^{131} of the machine adjacent the periphery of the hopper. As the hopper rotates further the wall l^{36} of the hopper (see Fig. 13) engages the roll l^{31} and holds the gripper toward the abutment l^{21} maintaining the grip on the wrapper edge m^4 . Figs. 11, 12 and 13 show this portion of the mechanism in three phases of its operation, viz. Fig. 11, immediately prior to engagement; Fig. 12, during the period when the strip is grasped and led forward; and Fig. 13, when the gripper is permitted to move out from the

wall of the hopper and thus release the free end m^4 of the wrapper blank M. This outward swinging movement of the gripper may be effected in any suitable manner, but I prefer to provide for accomplishing the release positively by the action of a coil spring l^{32} secured at one end, as at l^{33} , to the bottom of the hopper wall l^{28} and connected at its other end by a ligament l^{34} to the journal l^{24} which the ligament partly encircles near the arm l^{29} which carries the anti-friction roll l^{31} , the spring acting to open the gripper outward momentarily to effect release of the end m^4 when the roll l^{31} comes opposite a recess l^{35} (see Fig. 13) in the base l^{36} of the box l^{37} which incloses the hopper, (see Figs. 5 and 13). A pin l^{38} (see Fig. 11) may be provided to limit the outward swinging movement at the position shown in Fig. 9, which the gripper assumes after passing the dischargeway N, (see Fig. 5). The group of completed straps will have entered entirely within the slot l^2 , prior to severance of the rear end m^5 , and their pressure against the medial portion of the wrapper will have carried it into the slot l^2 , as shown in Fig. 5, drawing backward toward them the forward free end m^4 of the wrapper blank, which lies in the clearance space l^{19} between the hopper wall l^{28} and the box wall l^{37} , until this end occupies a position indicated by m^4 in Fig. 5, and the rotation of the hopper in the direction of the arrow Fig. 5 after severance of the end m^5 , now brings the free forward end m^4 opposite a vertical aperture l^{39} in the box wall l^{37} . The resiliency of the paper will throw the free end of the wrapper out into this aperture, so that as the hopper continues its rotation, the knife edge l^{40} of the aperture will engage the paper and fold it backward over the outermost strap of the group. To insure positive action of this knife edge, I prefer to form it as a swinging gate journal pivoted at l^{41} in the box wall and provided with a spring l^{42} tending to hold it normally inward toward the periphery of the hopper, which may be slightly recessed as indicated to receive the forward edge of the blade l^{40} .

There now remains the operation oflapping and pasting or otherwise securing the rearward free end m^5 of the wrapper-blank, to complete the packing and wrapping operations, and in accordance with the preferred embodiment of my invention, the hopper continues to rotate until it arrives at a quarter turn from the position at which the group of straps was introduced to the slot l^2 , or in other words, until the slot, with the group of straps, reaches the position of the slot l^3 in Fig. 5, with the rear end m^5 of the wrapper blank still trailing, however, as shown in Fig. 2, the wall l^{37} of the hopper box being broken

away to reveal the strap and wrapper. As a convenient form of device to bring about the lapping of this trailing end, I have shown a sliding folder-blade l^{43} carried by a segment l^{44} mounted in ways l^{45} within a suitable cutaway portion l^{46} of the box wall l^{47} , where it is secured by guide strips l^{47} , secured by screws l^{48} (see Fig. 2), and this folder is provided with a convex segmental rack l^{49} , with the teeth of which mesh the teeth of a pinion l^{50} mounted upon a vertical shaft l^{51} which rotates in bearings a^{132} upon the frame of the machine and has on its lower end another pinion l^{52} receiving a segmental rack l^{53} (see Fig. 9) at the end of an arm l^{54} , the other end of which is mounted pivotally upon a vertical shaft l^{55} (see Fig. 9) toward the rear of the machine, while a short arm l^{56} is provided with an anti-friction roll l^{57} (see Fig. 9), which enters and is actuated by a cam track a^{133} in the lower face of a disk cam a^{134} on the vertical shaft a^{114} , above the barrel cam a^{113} , (see Fig. 1). Before the forward folding movement of the folder l^{43} begins, I prefer to apply a suitable medium to secure the ends of the wrapper or inclosure, and in the instance illustrated this may be accomplished conveniently by pasting together the ends of the broad, flat paper strip of wrapping paper which constitutes the inclosure. As the preferred mode of accomplishing this pasting operation, I have shown means to apply paste to the outward surface of the trailing end m^5 , which will become the overlapping surface, and to permit this application of paste, I have shown the forward wall l^{58} (see Fig. 2) of the folder segment aperture as cut away at the points l^{59} , so that a series of brushes l^{60} carried by a paster arm l^{61} , (see Figs. 2 and 5), can reach the trailing end of the wrapper blank. The actuation of this paster may be accomplished in any suitable manner, and as one convenient form of actuating means, I have shown (see Fig. 2) a gear arm l^{62} on which the paster is mounted pivotally at l^{63} so that as the gear arm rotates about its pivot stud l^{64} , a cam l^{65} will engage the paster arm l^{61} and hold it away until the brushes with their burden of paste are opposite the trailing end m^5 , when the arm l^{61} escapes from the cam and a spring l^{66} forces the brush forward to apply the paste to the end m^5 through the apertures l^{59} . The parts designated by the reference numerals a^{135} and a^{136} respectively are protecting plates to prevent the moving parts from being engaged by the clothing of the operator. The gear arm l^{62} receives its motion from an intermediate gear l^{67} mounted upon a rock shaft l^{68} extending forward in bearings l^{69} and having at its end a gear l^{70} meshing with a lever gear l^{71} which is connected at its free end l^{72} by a link l^{73} to an adjustable screw stud l^{74} extending through a slot l^{75} .

in the head l^{70} of the link and tapped into the carriage l^{25} which operates the strap engaging arm l^{24} , with the rearward motion of which the pasting operation should correspond. A paste vat l^{77} is shown as provided adjacent the hopper in such a position that when the paster arm l^{61} is lowered the paster brushes l^{60} are applied to the periphery of a paste feeding roll l^{78} operated by a gear l^{79} (see Fig. 5) meshing with a pinion l^{80} on a shaft l^{81} which in turn carries (see Fig. 2) a gear l^{82} meshing with a pinion l^{83} upon a shaft l^{84} driven through the medium of a pulley l^{85} driven by a belt running to a suitable source of power not shown. The amount of paste fed is regulated by a movable bottom plate l^{86} , and front cap plates l^{89} secured in adjusted position by cap screws l^{90} serve to retain the roll-shaft l^{91} . The bottom plate is secured in adjusted position by screws l^{92} . The pasting operation having been accomplished, the folder segment l^{44} (see Fig. 5) slides forward in its ways into the position shown in Fig. 5, while the hopper is still at rest, and the loose folder edge l^{43} , which may be normally held inward by a spring l^{93} , enters behind the trailing end m^5 of the wrapper, the latter springing outward in front of the folder, and thereafter the folder wipes the trailing edge around into the position shown in Fig. 5, in contact with the lapping forward edge m^4 of the wrapper, and holds them in such contact until the hopper once more takes up its forward rotation, after which the contact between the lapping ends is maintained by engagement of the end m^5 with the box wall l^{37} . To prevent the spots of paste from being displaced during the wiping motion, I have shown the outer edge of the forward segment aperture jamb as grooved or cut away slightly as at l^{94} (see Fig. 2), thus leaving a clearance for the pasted spots.

By the above operations the straps have been arranged in their wrapper and the latter sealed in the form illustrated in Fig. 1^b, the straps presenting their uncovered ends preferably above the margin of the wrapper, so that they can be grasped easily by the workman and withdrawn from the wrapper, until its contents are completely exhausted. The wrapper is also open at the bottom, so that the workman can apply his finger to the loop end, or bight, of the straps and force them upward into position to be grasped and removed more readily.

The individual bundles of straps will be ejected severally by the action of the spring operated gates l^6 when any particular slct has in the course of rotation of the hopper reached the dischargeway N (see Fig. 5) at a point shown as distant three-quarters of a revolution from the point of introduction of the straps, giving the paste a chance to dry, although I do not limit myself to this point of discharge, nor to the specific mode of discharge. The dischargeway is shown as formed by a shelf n and wall, or walls, n' , along which the bundles travel outward, one by one.

The mechanism for rotation of the hopper and its support may be of any suitable construction, and as one convenient support, I have shown (see Fig. 9) the hopper as provided with a downwardly extending hub l^{95} secured by bolts l^{96} to central seats l^{97} (see Fig. 5) in the hopper and forming a vertical bearing l^{98} to receive and rotate about a vertical bearing post l^{99} mounted on the hopper base a^{137} which forms part of the main base of the machine. The rotation of the hopper is accomplished in the instance illustrated through the medium of a circular rack l^{100} extending downward from the bottom of the hopper and interrupted at quarterly intervals, as indicated at l^{101} , the teeth of the hopper meshing with the teeth of an interrupter gear a^{138} forming part of the structure of the cam a^{127} which is carried and actuated by the vertical shaft a^{114} . The hopper L rotates once for each four rotations of the gear a^{138} .

While the packing and wrapping or inclosing mechanism above described is of special utility where embodied in the construction of a machine of the class set forth, I wish it understood that I contemplate its utilization in any field to which it is adapted by the nature of my improvements, and it will be made the subject of generic claims in a separate application for United States Letters Patent.

Printing operation.—As it is usual in machines of the class described to provide mechanism for printing upon the straps the initials of the manufacturer, his trademark, or some other distinctive device, at such a region of the loop that it will be conspicuous after the strap has been secured upon the shoe upper, I have illustrated herein one form of printing mechanism which may be embodied conveniently in the construction of an organized machine embodying my improvements, although I do not limit myself to the use of this particular form of printing mechanism, nor indeed to the use of any printing device.

The printing mechanism illustrated (see Fig. 2; also Figs. 1 and 4) comprises an arm P mounted pivotally near one end, as at p , upon a bearing bracket p' , on the machine, and having a link p^2 and pin p^3 connection with a crank shaft p^4 , the latter being actuated by a spiral gear p^5 meshing with a spiral gear p^6 on a clutch member p^7 mounted freely on the main shaft a^{67} . Upon each forward movement of the arm P , which is arranged to occur during the dwell of the strip portion a^{43} opposite the platen a^{44} ,

prior to the feeding operation, the arm P presses against the strip a die or other form of printing means p^8 , which may be, and preferably is, secured adjustably, as by screws p^9 within a chase p^{10} , so that the form can be arranged to engage the proper region of the strip regardless of the length of the completed strap. To provide ink for the die, I have shown a rotating ink disk p^{11} , of well-known form, mounted upon an upright inclined shaft p^{12} , carried rotatively in suitable bearings supported by an arm p^{13} extending from the frame members a^{13} to which it is secured by suitable fastening means, and to transfer the ink to the die from the disk, an inking roller p^{14} is shown, carried by an armlike lever p^{15} having an elbow joint p^{16} and an upper arm portion p^{17} mounted upon a rock shaft p^{18} and having a pawl p^{19} (see Figs. 2 and 4) which engages intermittently the teeth of a disk shaft ratchet gear p^{19} . A latch p^{20} prevents reverse movement of the disk, by engaging the teeth of the ratchet gear p^{19} , and a screw p^{21} may be provided to regulate the operation of the pawl p^{19} , the latter having a spring p^{22} to hold it normally in engagement with the ratchet, (see Fig. 4). The rock shaft p^{18} has a crank p^{23} , (see Figs. 1 and 5) connected by a link with the spiral gear p^5 which, as already described meshes with the spiral gear p^6 carried by the clutch member p^7 , mounted freely upon the main shaft a^{67} . The shaft has another clutch member p^{24} (see Fig. 2) connected rotatively with it by a pin p^{25} which transfixes also the inner end of a rod p^{26} lying in a recessed portion a^{141} , formed preferably as an axial bore, in the actuating shaft, from the outer end of which the rod projects and is provided with a controlling knob p^{27} . This knob has in turn (see Fig. 5) a shoulder p^{28} which when the knob is pulled outward and given a quarter turn will engage the end of the shaft, and when so engaged, the clutch members will be connected, as shown in Fig. 5, and will rotate with the shaft, and the inking mechanism will be actuated. The end of the shaft a^{67} is provided with a groove or notch a^{142} , and when the knob shoulder p^{28} is brought opposite this notch and the knob is released, a spring p^{29} (see Fig. 2) surrounding the rod p^{26} within the bore a^{141} and confined between a shoulder on a reduced part of the rod and a bushing a^{144} in the end of the shaft, (see Fig. 4, the knob p^{27} being omitted to show the end of the bushing,) throws the rod and clutch rearward out of engagement with the other clutch member, stopping the printing mechanism. To start the printing mechanism again, the knob p^{27} is pulled outward until the shoulder p^{28} escapes from the notch a^{142} and turns opposite the portion a^{143} of the shaft end. (See Fig. 2.)

The reference letters a^{143} and a^{146} , (see Fig. 4) designate respectively guard plates, one for the main actuating gear and pinion, and the other for the front of the machine, a^{147} being one of the supporting posts for the front plate.

Having described my invention, what I claim as new and desire to secure by Letters Patent of the United States is:—

1. A machine for manufacturing shoe straps; said machine comprising covering mechanism, doubling mechanism, and packing mechanism acting upon said shoe-straps in the order named, and being organized to manufacture and deliver packages in 75 80 85 89 closures each containing a plurality of covered and doubled shoe straps.

2. A machine for manufacturing shoe straps; comprising covering, doubling and 85 90 95 packing mechanisms constructed and arranged to receive strap, cover and inclosure stock; said mechanisms acting upon said articles in the order named, and being organized to manufacture said cover and strap stock into a plurality of covered, doubled straps; also to pack said covered, doubled straps in a bundle, and to apply to said bundle said inclosure stock, leaving said straps removable individually until exhaustion of said bundle.

3. A machine for manufacturing articles of the class described from substantially continuous strips of work, cover and inclosure stock; said machine comprising supports for said stock strip supplies respectively; a tension and detector device; marking mechanism; severing mechanism; a retaining member to hold the stock end of said work strip after severance; a yielding folding-table; a reciprocating gripper device to grasp said severed stock-end and draw successive supplies of work-strip past said detector, marking, retaining and severing devices respectively, and over said table; mechanism to feed successive supplies of cover stock transversely between said table and work-strip, and means to sever suitable portions from said cover strip; a divided templet blade movable toward said table; folder members on opposite sides of said table to engage said cover material upon depression of said table and cover material under the action of said templet, and means to move said folder members transversely to overlap the edges 110 115 120 125 130 of said cover material upon said templet; a creasing device to engage said covered article and withdraw it transversely between the portions of said templet; doubling mechanism to receive said covered article bight forward from said creasing device and compress said article; assembling mechanism to receive said articles *seriatim* from said doubling mechanism; an assembly way into which said articles are introduced suc-

- cessively by said assembling mechanism; a packing receptacle to receive said covered, doubled articles from said assembly way; mechanism to interpose a portion of enclosure material in the path of each group of said articles from said assembly way to said packing receptacle and to sever said enclosure blanks; means to compact said assembled articles and transfer them and said 5 10 15 20 25 30 35 40 45 50 55 60 65 70 75 80 85 90 95 100 105 110 115 120 125 130
- inclosure into said packing receptacle; and means to fasten the ends of each of said enclosures to secure it in place upon its pack.
4. In a machine for manufacturing covered shoe-straps; mechanism for applying to said shoe-straps covering material of an inert character capable of receiving a permanent set; and mechanism for securing said covering material permanently upon said articles by retentive contact of its parts exclusively, and without the use of an extraneous adhesive upon any portion of said strap, said mechanism setting said material to cause said retentive contact.
5. In a machine for manufacturing shoe-straps; covering mechanism; doubling mechanism; packing mechanism; and mechanism to maintain each of said covers upon its respective shoe-strap without an extraneous adhesive during said covering, doubling and packing operations.
6. In a machine for manufacturing shoe-straps; mechanism for applying a cover to each of said straps; mechanism to double said covered straps respectively; mechanism to pack said covered, doubled straps *seriatim* as delivered from said covering and doubling mechanisms; and means to maintain each of said covers upon its respective strap by retentive contact of its parts exclusively during said covering, doubling and packing operations.
7. In a machine for covering strips of flexible material; a templet having a transverse exit; mechanism to associate said strip and templet; mechanism to apply covering material to said strip and templet; and means to dissociate said templet and covered strip; substantially as described.
8. In a machine for covering strips of flexible material; a flat templet, divided transversely into a plurality of templet members; mechanism to associate said strip and templet; mechanism to apply covering material to said strip and templet; and means to dissociate said templet and the covered strip; substantially as described.
9. In a machine for covering strips of flexible material; a flat templet, divided transversely into a plurality of blades lying in the same general plane, with their free ends opposed; mechanism to associate said strip and templet; mechanism to apply covering material to said strip and templet; and means to withdraw said covered strip from said templet members transversely be-
- tween their adjacent free ends; substantially as described.
10. In a machine for manufacturing covered articles of the class described; mechanism to present said articles respectively in position to be covered; a templet device arranged to be covered with said article; mechanism to apply said covering material to said article and templet; and means to withdraw said covered article transversely from said templet; substantially as described.
11. In a machine for manufacturing covered articles of the class described; mechanism to present said articles respectively in position to be covered; a templet device arranged to be covered with said articles and having a medial, transverse exit; mechanism to apply said covering material to said article and templet; and means to withdraw said covered article transversely from said templet through said exit.
12. In a machine for covering articles of the class described; mechanism to present said articles respectively in position to be covered; a templet device comprising a plurality of flat blades, and means to support the said device adjacent each article with the free ends of said blades separated; means to apply covering material to said article and templet; and means to withdraw said covered article from said blades transversely between the free ends thereof.
13. A templet device for machines of the class described; said device comprising a plurality of templet members, and means to support the same with a free end of one of said members opposed to the free end of another of said members; substantially as described.
14. A templet device for machines of the class described; said device comprising a plurality of flat templet members, and means to support the same in the same general plane with a free end of one of said members opposed to the free end of another of said members; substantially as described.
15. A templet device for machines of the class described; said device comprising a lever provided with a medial bearing portion and having one of its arms arranged for engagement with suitable operating mechanism, the other arm of said device being provided with a yoke, and a plurality of templet plates secured to said yoke and bridging the same with their free ends separated.
16. A templet-device for folding mechanism for apparatus of the class described; comprising a support-member and a plurality of templet-plates extending toward each other from the arms of said support respectively, the neighboring ends of said plates being separated, concave and having their outer corners depressed.

17. A templet member for machines of the class described; said member comprising a flat blade arranged to be secured at one end to a suitable support, and having its other end cut away concavely, and its corners bent out of the plane of said blade. 70
18. In a machine for covering articles of the class described; means to support one of said articles and covering material therefor, in juxtaposition; a templet device movable to engage said article and to force the same toward said supporting means with said covering material interposed between said article and supporting means; mechanism to fold said covering material around said article and embracing said templet device also; and mechanism to crease said covered article transversely to said supporting means and to withdraw said article transversely from said templet. 15
19. In a machine for covering strips of the class described; a work table; mechanism for arranging the work-strip and a covering-strip one over the other over said work table; a templet device to hold said superimposed strips in position for the covering operation; means to fold said covering-strip over said work-strip and templet; and means to withdraw said covered work-strip transversely from said templet. 20
20. In a machine of the class described, a folding-table having a central exit; mechanism to feed a strip of covering material over said table; mechanism to draw a strip of stock over said table and cover material; a folder on each side of said table; a templet device to press said stock-strip against said table past said folders to cause flexure of the edges of said cover, said templet also having a central exit; mechanism to operate said folders to overlap said edges about said templet; doubling mechanism opposite said exits; and a creasing device to engage the overlapping edges of said cover and press the same, with said strip inclosed, through said exits into said doubling mechanism. 25
21. Folding mechanism for apparatus of the class described; said folding mechanism comprising a yielding folding-table to receive the article to be folded; and a folder member near said table and arranged to engage said article and bend the same, upon traverse of said folder member by said table and article, said folder member being constructed and arranged to permit withdrawal of said folded article transversely while said folder is in operative relation with said table; substantially as described. 30
22. Folding mechanism for apparatus of the class described; said folding mechanism comprising a yielding folding-table to receive the article to be folded; and a plurality of folder members near said table and arranged to engage said article and bend the same, upon traverse of said folder member by said table and article, said folder member being movable above said table to bend said article back upon itself; a templet member arranged to be superposed upon said article between said folder members, and over which said article may be formed thereby, and being constructed and arranged to permit transverse withdrawal of said article. 35
23. Folding mechanism for apparatus of the class described; said folding mechanism comprising a yielding folding-table to receive the article to be folded; and a folder member near said table and arranged to engage said article and bend the same, upon traverse of said folder member by said table and article; said folder member being movable above said table to bend said article back upon itself, and being constructed and arranged to permit transverse withdrawal of said article. 40
24. Folding mechanism for apparatus of the class described; said folding mechanism comprising a yielding folding-table to receive the article to be folded; a folder member near said table and arranged to engage said article and bend the same, upon traverse of said folder member by said table and article; and a templet member arranged to be superposed upon said article to restrain the portion adjacent to said bend, and being constructed and arranged to permit transverse withdrawal of said article. 45
25. Folding mechanism for apparatus of the class described; said folding mechanism comprising a yielding folding-table to receive the article to be folded; a folder member near said table and arranged to engage said article and bend the same, upon traverse of said folder member by said table and article, said folder member being movable above said table to bend said article back upon itself; and a templet member arranged to be superposed upon said article between said folder members, and over which said article may be formed thereby, and being constructed and arranged to permit transverse withdrawal of said article. 50
26. Folding mechanism for apparatus of the class described; said folding mechanism comprising a yielding folding-table to receive the article to be folded; a folder member near said table and arranged to engage said article and bend the same, upon traverse of said folder member by said table and article, said folder member being movable above said table to bend said article back upon itself; a templet member arranged to be superposed upon said article between said folder members, and over which said article may be formed thereby; means to force said templet and table, with said intervening article, between said folder-members, and means to withdraw said article transversely through said templet, table and folders. 55
27. Folding mechanism for apparatus of the class described; said folding mechanism comprising a yielding folding-table to receive the article to be folded; a folder member near said table and arranged to engage said article and bend the same, upon traverse of said folder member by said table and article, said folder member being movable above said table to bend said article back upon itself; and a templet member arranged to be superposed upon said article between said folder members, and over which said article may be formed thereby, and being constructed and arranged to permit transverse withdrawal of said article. 60

comprising a yielding folding-table to receive the article to be folded; a folder member near said table and arranged to engage said article and bend the same, upon traverse of said folder member by said table and article, said folder member being movable above said table to bend said article back upon itself; a templet member arranged to be superposed upon said article 10 between said folder members, and over which said article may be formed thereby; means to force said templet and table, with said intervening article, between said folder-members; and means to impart folding over 15 movement to said folder-members.

28. In a machine of the class described, a yielding folding-table; mechanism to feed cover-material thereupon; mechanism to feed the article to be covered above said cover 20 material; a folder-member adjacent said folding-table; and means to move said folding-table past said folder-member to bend said cover over the edge of said article to be covered; and means to withdraw said article 25 transversely through said table and folder; substantially as described.

29. In a machine of the class described; a yielding folding-table; mechanism to feed cover material thereupon; mechanism to 30 feed the article to be covered above said cover material; a folder member adjacent said folding-table; and means to engage said article and press it with said cover and folding-table past said folder-member, to 35 bend said cover past the edge of said article; and means to withdraw said article transversely through said table and folder; substantially as described.

30. In a machine of the class described; 40 a yielding folding-table; a templet reciprocable in the line of movement of said table; a plurality of folder-members reciprocable over said table at an angle to said line of movement; and means to introduce cover 45 material and the article to be covered intermediate said table and templet between said folder members; said mechanisms coöperating to apply said cover material to said article.

50. 31. In a machine of the class described; the combination with a folding-table; means to feed cover material thereupon; mechanism movable above said table to place a work-strip above said covering material; 55 and folding means to bend said covering material around said work-strip; of a templet device having a transverse, medial exit, and means to associate said templet device with said work-strip and covering device with said work-strip and covering 60 material for said folding operation, means to double said covered strip in place, and means to withdraw said device to clear said table for the feeding operation, after dis- 65 sociation of the covered strip from said templet.

32. A yielding folding-table for machines of the class described; comprising a support; a plate having a central aperture with rounded edges; a plurality of posts extending from the lower surface of said plate to 70 enter sockets in said support; and a coil spring around one of said posts to support said folding-table yieldingly.

33. In a machine of the class described; 75 a templet having a central clearance opening; folders, comprising elongated folder-blades each having also a central clearance opening; and a creasing device to pass through said clearance openings into engagement with the article to be treated, 80 withdrawing said article slidingly from between said folders and templet, and doubling said article transversely.

34. Folding mechanism for machines of the class described; comprising elongated, 85 horizontal folding-blades; upright arms to support said folding-blades; and an upright cam having lateral shoulders to actuate said arms; said arms being carried by extended medial, horizontal rock-shafts mounted in 90 bearings on the frame of said machine, and having at their lower free ends anti-friction devices between which move said cam shoulders, the latter being arranged to cause approach toward each other of the upper 95 free ends of said arms with their attached folder blades, one slightly in advance of the other.

35. Creasing mechanism for apparatus of the class described: comprising an arm having a medial bearing to receive a horizontal shaft mounted on a machine frame and having at its upper free end a creasing blade, the lower portion of said arm having an anti-friction device to enter and be operated upon by a cam-track in the face of a cam mounted on a cam shaft geared operatively to the main actuating shaft.

36. Doubling mechanism for articles of the class described: comprising a pair of 110 doubling rolls between which the article is pressed after having been covered; and a pair of delivery rolls, one having a yieldable bearing, to receive said article from said doubling rolls, and to deliver the same; substantially as described.

37. Doubling mechanism for apparatus of the class described: comprising a pair of doubling rolls to receive and press the article to be doubled; a pair of similar compressing and delivery rolls; and endless delivery belts intermediate said pairs of rolls to carry said article from one pair to the other.

38. Doubling mechanism for apparatus of 125 the class described: comprising an upper pair of doubling rolls to receive and press the article to be doubled; a lower pair of rolls; and endless delivery belts intermediate said pairs of rolls to carry said article 130

- from one pair to the other, said rolls having respectively peripheral grooves near each end, and said conveying belts consisting of four endless helical springs lying in said grooves.
39. A machine for manufacturing covered shoe-straps; said machine comprising covering mechanism, mechanism to double said covered shoe-straps, respectively, and mechanism for assembling said covered and doubled straps in regular order and predetermined quantities; substantially as described.
40. A machine for manufacturing covered shoe-straps; said machine comprising covering mechanism, mechanism to double said covered shoe-straps, respectively, an assemblatory, and mechanism for assembling said covered and doubled straps in regular order and predetermined quantities within said assemblatory.
41. In a machine of the class described; the combination with doubling mechanism; of assembling mechanism comprising a rotating member having a receiving portion to which said doubling mechanism delivers the doubled articles, *seriatim* and bight forward; means to confine said articles within said receiving portion in such a manner as to cause them to be advanced by said rotation; and a suitable assemblatory adjacent to the discharge end of said receiving portion, into which assemblatory said rotating member delivers said articles face to face, with their bights all in the same direction.
42. In a machine of the class described; the combination with covering mechanism and doubling mechanism; of assembling mechanism comprising a rotatable screw having a spiral groove to which are delivered from said doubling mechanism the covered, doubled articles, bight forward; means to confine said articles within said groove so as to cause their advance by said rotation; an assemblatory adjacent to the discharge end of said groove, into which assemblatory said screw delivers said articles face to face, with their bights all in the same direction; and packing mechanism to receive said assembled articles and inclose the same in merchantable units each containing a plurality of said articles, and each pack having an inclosure from which said articles may be withdrawn individually until exhaustion of said pack.
43. In a machine for manufacturing articles of the class described; the combination with covering mechanism and doubling mechanism, of assembling mechanism comprising an assemblatory arranged to receive a plurality of the articles to be assembled; and means to pack said articles in groups in said assemblatory, and to transfer said packs successively therefrom, substantially as described.
44. In a machine for manufacturing articles of the class described; the combination with covering mechanism and doubling mechanism, of assembling mechanism comprising an assemblatory; means to introduce thereto the articles to be assembled, in a relatively loose group; and means to compress and discharge said group from said assemblatory in a compact pack; substantially as described.
45. In a machine for manufacturing articles of the class described; the combination with covering mechanism and doubling mechanism, of assembling mechanism comprising an assemblatory; means to introduce thereto the articles to be assembled, in a relatively loose group; means to compress and discharge said group from said assemblatory in a compact pack; and means to secure said pack in said compact form; substantially as described.
46. In a machine for manufacturing articles of the class described; the combination with covering mechanism and doubling mechanism, of assembling mechanism comprising a packing member, and a restraining member, coöperating to engage, pack and transfer the assembled articles; substantially as described.
47. In a machine for manufacturing articles of the class described; the combination with covering mechanism and doubling mechanism, of assembling mechanism comprising an assemblatory; means to introduce a plurality of articles thereto and means to resist yieldingly said introduction of said articles, thereby to form a pack; a packing member to enter said assemblatory at the rear of said pack and move the same forward therein; and means to withdraw said restraining means from said assemblatory to release said pack; substantially as described.
48. In a machine for manufacturing articles of the class described; the combination with covering mechanism and doubling mechanism, of assembling mechanism comprising an assemblatory; a packing receptacle in communication therewith; means to introduce a plurality of articles to said assemblatory; means to resist yieldingly said introduction, thereby to form a pack, a packing member to enter said assemblatory at the rear of said pack and transfer the same to said receptacle; means to withdraw said restraining means to release said pack from said assemblatory; and means to resist yieldingly the entrance of said pack to said receptacle; substantially as described.
49. In a machine for manufacturing articles of the class described; the combination with covering mechanism and doubling mechanism, of assembling mechanism comprising an assemblatory; means to introduce thereto a plurality of the articles to be as-

sembled; a packing member to select, pack and transfer in succession groups each containing a predetermined number of said articles; a device to restrain yieldingly the forward movement of said articles in said assemblatory prior to packing; and means to change said restraining device from the front of said group to the rear of said packing member after selective engagement by 10 said packing member with each group; substantially as described.

50. In a machine for manufacturing articles of the class described; the combination with covering mechanism and doubling mechanism, of assembling mechanism comprising an assemblatory; means to introduce thereto a plurality of articles to be assembled; a restraining device; a packing member, and means to introduce said device and member alternately into said assemblatory to engage the front and rear respectively of successive groups of said articles to pack the same; substantially as described.

51. In a machine for manufacturing articles of the class described; the combination with covering mechanism and doubling mechanism, of assembling mechanism comprising an assemblatory; means to introduce thereto a plurality of articles to be assembled; a reciprocating restraining member; a reciprocating packing member; and means to introduce said device and member alternately into said assemblatory to engage the front and rear respectively of successive groups of said articles to pack the same; and means to return said device and member periodically to their respective points of entry to said assemblatory; substantially as described.

52. In a machine for manufacturing articles of the class described; the combination with covering mechanism and doubling mechanism, of assembling mechanism comprising an assemblyway to receive the articles to be assembled; a restraining device in said assemblyway to engage the foremost of said articles as received and tending to oppose yieldingly advance of said articles into said assemblyway; and mechanism to withdraw said restraining device from the path of said articles after assemblage of a predetermined number of said articles, and to return said restraining device to its original point of departure in advance of a fresh group of articles to be assembled.

53. In a machine for manufacturing articles of the class described; the combination with covering mechanism and doubling mechanism, of assembling mechanism comprising an assemblyway; a rock-rail mounted to oscillate about a longitudinal axis near said assemblyway; a carriage to traverse said rail longitudinally; and an arm movable with said carriage and having a finger arranged for projection within said assem-

blyway and for withdrawal therefrom by rocking movement of said rail; said carriage being advanced in one direction along said rail by engagement with said finger of the forward article of a group of articles to be assembled, as they are successively introduced to said assemblyway; means to rock said rail to withdraw said finger from said engagement, after assembly of a predetermined number of said articles; means to hold said finger in yielding opposition to the advance of said articles, said means acting upon withdrawal of said finger to return said finger to its point of original departure; and means to rock said rail forward to introduce said finger in front of a fresh group of articles to be assembled.

54. In a machine for manufacturing articles of the class described, the combination with covering mechanism and doubling mechanism, of assembling mechanism comprising a rock-rail of rectangular section provided near one end with an enlargement and a cam-engaging portion and having at its other end a removable head provided with a buffer; a carriage consisting of a frame to embrace three sides of said rail snugly and having retaining projections to engage the fourth side thereof, said carriage being provided with an antifriction device on its forward end to engage the upper surface of said rail, a similar device on its rear to engage the lower surface thereof, and an upwardly extending finger mounted adjustably on said carriage; a support for said rail; and adjustable bearing-pivot-screws extending through said support into engagement respectively with said rail ends; a spring extending from said support to said carriage and tending normally to draw the same into engagement with said buffer; a spring tending normally to rock said rail and finger forward; and a cam having a portion to engage said cam-engaging portion of said rail to rock said rail and finger rearward at times, said cam being mounted on and rotatable with a cam-shaft, provided with a gear in engagement with, and actuated by a gear on the main actuating shaft of said machine; substantially as described.

55. In a machine for manufacturing articles of the class described; the combination with covering mechanism and doubling mechanism, of assembling mechanism comprising an assemblyway; mechanism to introduce thereto a plurality of articles; and means to enter said assemblyway at the rear of said articles, to pack the same and to move said pack forward and discharge the same from said assemblyway.

56. In a machine for manufacturing articles of the class described; the combination with covering mechanism and doubling mechanism, of assembling mechanism comprising an assemblyway; means to introduce

- thereto a plurality of articles to be assembled; a rock-shaft mounted near said assemblyway; a carriage to traverse said rock-shaft and provided with an arm having a projection to be introduced by rocking of said shaft into said assemblyway at the rear of said assembled articles and movable therein to pack said articles; a cam connected with, and to be operated by, the main operating shaft of said machine; an arm connected at one end to said rock-shaft, and having at its free end an anti-friction roll in engagement with and to be operated by a peripheral track upon said barrel cam to rock said shaft at times and a lever having a portion to engage and reciprocate said carriage to pack said articles, and a portion to engage and be operated by said cam, substantially as described.
57. In a machine for manufacturing articles of the class described, said machine having a support, an assemblatory, and a main actuating member, the combination with covering mechanism and doubling mechanism, of packing mechanism comprising a rock-shaft mounted at its ends rotatively on said support and provided with a rocking lever and a plurality of arms carrying an auxiliary rock-rod, a carriage having bearings traversed by said rock-shaft and rock-rod respectively, said carriage presenting rearwardly a rack, and having an upwardly extending packing member to enter said assemblatory and cause to move therein a plurality of assembled articles; a vertical shaft connected with, and to be operated by, said main actuating member, and a barrel cam on, and actuated by said vertical shaft, said cam having a ledge track to engage said rock-lever to rock said rock-shaft and rock-rod at times to withdraw said packing member from said assemblatory; a spring tending normally to hold the packing portion of said packing member in said assemblatory; and operating lever mounted to oscillate upon a vertical axis and having an arm provided with means to engage and be operated reciprocatingly by a face track on said cam, and a segmental rack at the free end of said operating lever and meshing with said carriage rack; rotation of said cam causing reciprocation of said packing member, its forward movements serving to advance said articles in said assemblatory, and its rearward movements being accomplished outside of said assemblatory, substantially as described.
58. In a machine for manufacturing covered articles of the class described; the combination with covering mechanism; of mechanism for positioning the strip of material to be covered, said positioning mechanism comprising a sliding head provided with jaws to grasp the free end of said strip, one of said jaws being movable; and mechanism

to engage a part connected with said movable jaw to close said jaws positively upon said material and thereafter by continued engagement and pressure upon said movable jaw-part to move said sliding head and draw said strip into covering position.

59. Positioning mechanism for machines of the class described; comprising a slideway; a gripper head movable thereon and provided with a jaw and with shaft bearings; a shaft carried in said bearings and having a jaw movable to coöperate with said other jaw to grasp a strip of material; and an operating member operable to rotate said shaft to open and close said jaw, and by its further movement to cause said head to traverse said slide reciprocatingly, forward to draw said stock into position to be covered, and backward to receive a fresh supply of stock.

60. In a machine of the class described; strap positioning mechanism comprising a slideway: a gripper head movable thereon and having a transverse arm provided with a fixed jaw and with shaft bearings; a shaft carried in said bearings on said transverse arm and having a jaw movable to coöperate with said other jaw and grasp a strip of strap stock; a crank upon the other end of said shaft, said crank having a pin and block; and a lever mounted pivotally near said crank and having a groove to receive said pin-block; said lever being operable to rotate said crank to open and close said jaw and by its further movement to cause said head to traverse said slide reciprocatingly, forward to draw said strap stock into position to be covered, and backward to receive a fresh supply of stock.

61. In a machine of the class described, having a frame; a slideway, covering mechanism, a cam shaft, and a main actuating shaft, all mounted on said frame; a gripper head mounted on said slideway; an operating lever mounted pivotally near one end on said frame and engaging said gripper head operatively with its free portion; an actuating lever mounted pivotally near one end on said frame and having a movable connection with the medial portion of said operating lever; a cam, mounted upon said cam shaft, and having a track adjacent said actuating lever; means upon the free portion of said actuating lever to engage said cam-track, thereby to permit actuation of said gripper head by said cam-shaft; and operating connections intermediate said actuating shaft and said cam-shaft.

62. A gripper device for machines of the class described; comprising a head arranged to receive and be mounted upon a slideway and having an adjustable wear block to engage with said slideway, a transverse bearing sleeve, and a fixed jaw portion; a rock-shaft in said sleeve and having a jaw ro-

- tatable to coöperate with said fixed jaw; a crank connected operatively with said rock-shaft and a pin extending from the free portion of said crank; an adjustable 5 abutment upon the lower portion of said head to engage said pin at times and limit the opening movement of said jaw; and an operating lever for said pin; substantially as described.
- 10 63. A gripper-head for machines of the class described; said head comprising a slide-engaging portion; and a transverse bearing portion provided with a jaw member and having a shaft bearing to receive a shaft 15 with a coöperating movable jaw member.
64. In a machine of the class described, having a support; a movable gripper device and an actuating cam; a compound actuating lever comprising an operating member mounted pivotally on said support and arranged to engage said movable gripper member with its free portion; an actuating member mounted pivotally on said support and extending past said operating member 20 in the opposite direction, with its free portion connected to, and arranged to actuate, said operating member, said actuating member having a cam-engaging portion; substantially as described.
- 25 65. In a machine of the class described; a support; a movable gripper member and an actuating-cam carried thereby; a compound actuating lever comprising an operating member mounted pivotally on said support and having a slot in its medial portion and a groove at its free end; a pin and block on said movable gripper member to enter said groove; an actuating lever mounted pivotally on said support, and extending past 30 said operating member in the opposite direction, said actuating member having a groove in its free end and a medial projection to engage and be actuated by said cam; and a block arranged to slide in the groove 35 of said actuating lever and connected with said operating lever by suitable fastening means adjustable in said slot, to permit said cam to impart to said movable member a variable motion, of predetermined extent; 40 substantially as described.
- 45 66. In a machine of the class described; mechanism for feeding a stock-strip; a support for a supply of said stock; and a tension device to engage said strip intermediate said feeding mechanism and said supply support; said tension device comprising a plurality of arms mounted pivotally near one end on a suitable support and normally depending therefrom, said arms carrying between their free ends a primary idler beneath which said strip is led from said supply support, the weight of said idler and of its supporting arms serving to draw a fresh supply of stock from said supply support 55 after each feeding operation and acting as a yielding drag during said feeding operations; and a secondary or auxiliary tension frame carried between said arms and comprising a pair of arms mounted pivotally within said main arms and carrying between their free ends a secondary idler around which said stock strip is led from said primary idler to said feeding mechanism, said strip tending, by reason of the sudden drag upon it during the feeding operation, to displace said auxiliary frame about the arm pivots and also to raise said tension device from its normally depending position, and means tending normally to resist displacement of said auxiliary frame from its normal position relatively to said main tension frame; 60 substantially as described.
- 65 67. In a machine of the class described; the combination with covering mechanism and stock positioning mechanism, of an abutment, and a tension and detector device acting upon the strip of stock to hold the same normally against said abutment and under tension; and mechanism operated by said device to stop the operation of said machine at times; substantially as described.
- 70 68. In a machine of the class described; an abutment to be traversed by a strip of stock; a shipping lever; a rock shaft provided with a detector and an operating portion, connections between said shipping lever and operating portion; and means tending to rotate said rock shaft into position to hold said detector normally toward said abutment with said strip interposed 75 therebetween, said means acting upon failure of said strap, or variation in the normal thickness thereof, to rotate said shaft and shoulder and by means of said connections to cause operation of said shipping lever to 80 stop the operation of said machine.
- 75 69. In a machine of the class described; the combination with a shipping lever and an abutment traversed by a strip of stock; of a rock shaft provided near one end with a knuckle arranged to be held in normal position by engagement with said strip against said abutment, and a shoulder at the other end of said rock shaft; a latch mounted pivotally upon the frame of said machine, said latch normally lying across and upon said shoulder and extending into position to engage at times a part of said shipping lever, to hold said shipping lever in position to cause operation of said machine; and means tending to rotate said rock shaft to press said knuckle toward said abutment, failure of said strip permitting said spring to rotate said rock shaft and shoulder and thereby acting to raise said latch to throw off said shipper handle and stop said machine; said rotation being accomplished in an opposite direction upon engagement with said knuckle of a thickened portion of said strap, whereupon the 85
- 80 90 95 100 105 110 115 120 125 130

other end of said shoulder will throw off said latch and shipper handle.

70. A controlling device of the class described, comprising a controller shaft and a 5 knuckle member connected to rotate therewith and provided with manually operable actuating means; means tending normally to rotate said shaft toward an abutment; and a latch rotatable on said shaft into position to permit introduction of a work-strip 10 between said knuckle and abutment, and into another position to retain said strip in adjusted position.

71. In a machine of the class described; 15 the combination with stock-strip feeding mechanism, of mechanism to regulate the length of the article to be manufactured; said regulating mechanism comprising a member movable relatively to said feeding 20 mechanism and arranged to be secured in adjusted position upon the frame of said machine, said member having a sill above which said strip is carried, a presser foot mounted pivotally above said sill and between which and said sill said strip is to be carried, and a spring to hold said presser foot normally toward said sill; a fixed shear upon said movable member and a rock shaft mounted in bearings upon said movable 30 member and provided with a knife to coöperate with said fixed shear; and operating means for said rock shaft; substantially as described.

72. In a machine of the class described; a 35 support; a member movable on said support and provided with strip severing mechanism comprising a rock-shaft mounted in bearings on said member and having a shear and an operating gear-member; a rock-shaft 40 mounted in bearings on said support and having an actuating gear-member arranged to intermesh with said operating gear-member regardless of the adjusted position of

said movable member; and means to operate said actuating gear-member; substantially 45 as described.

73. In a machine of the class described; a frame; strip-doubling mechanism and a marking platen mounted on said frame in fixed relative positions; an adjustable strip-severing device; and a direction member arranged to maintain said strip in position for marking, regardless of the adjusted position of said strip-severing device; substantially 50 as described. 55

74. In a machine of the class described; a frame; strip feeding mechanism and strip severing mechanism mounted on said frame, with means to regulate the length of strip portions severed; and a marking device also 60 mounted on said frame in fixed position and having marking means adjustable independently of said length-regulating means to mark said strip portions successively, prior to their severance, and at a predetermined 65 region corresponding to their length; substantially as described.

75. In a machine of the class described; a support; a direction device comprising an arm secured to the said support; a latch 70 mounted pivotally upon said support adjacent said arm and having a gate-piece adjustable to conform to the width of the strip of stock, said latch being rotatable about its pivot to swing said gate away from said 75 arm to permit introduction and displacement of said strip; and means to hold said latch in adjusted position; substantially as described.

In testimony whereof I have signed my 80 name to this specification in the presence of two subscribing witnesses.

EDWARD A. STIGGINS.

BERNARD BARROWS,
FREDERICK L. EDMANDS.

Copies of this patent may be obtained for five cents each, by addressing the "Commissioner of Patents, Washington, D. C."

It is hereby certified that in Letters Patent No. 1,127,541, granted February 9, 1915, upon the application of Edward A. Stiggins, of Beverly, Massachusetts, for an improvement in "Machines for Covering Boot and Shoe Straps," errors appear in the printed specification requiring correction as follows: Page 3, line 17, for the word "temple" read *templet*; page 6, line 5, for the word "plan" read *plane*; page 10, line 71, for the reference-letter "l" read *l*"; page 11, line 89, for the word "interrupter" read *interrupted*; page 15, line 66, for the word "yielding" read *yielding*; and that the said Letters Patent should be read with these corrections therein that the same may conform to the record of the case in the Patent Office.

Signed and sealed this 7th day of September, A. D., 1915.

[SEAL.]

J. T. NEWTON,

Acting Commissioner of Patents.
